UNITED STATES PATENT OFFICE.

FREDERICK EUGENE PERNOT AND LESTER JACOB RICH, OF LONDON, ENGLAND.

MULTIPLEX TELEGRAPHY.

Application filed March 10, 1923, Serial No. 624,224, and in Spain March 15, 1922. Renewed June 7, 1926.

This invention has reference to improvements in and applicable to multiplex telegraphy and has particular, although not exclusive, reference to the means for and the method of transmitting the receiving electric current signals over submarine cables.

The principal object of the present invention is the provision of improved means 10 for enabling duplex direct current and either simplex or multiplex alternating current to work simultaneously over one and the same cable.

Further objects of this invention are the 15 provision of means for increasing the selectivity of the circuits and for eliminating or minimizing interference between the several currents in the circuits and of improved means for effecting adjustment of the alternating current receiving apparatus.

The principal feature of this invention consists in the provision and arrangement in a system for multiplex telegraphy employing superposed duplex direct current 25 and either simplex or multiplex alternating current of a "transient moderator" comprising, for example, networks of impedances which serve to eliminate or minimize disturbance of the local alternating current 30 receiver or receivers by local transmitted direct current.

Another feature consists in so introducing and removing the local alternating current electromotive force or forces that the remote 35 direct current receiver may be sensibly unaffected by currents produced thereby.

Further features of this invention will be evident from examples of carrying the invention into effect hereinafter described.

40 Figure 1 of the accompanying diagrammatic drawings represents one method of carrying out this invention.

Figure 2 represents in detail one arrangement according to the present invention for 45 minimizing disturbance of the remote direct current receiver by locally transmitted alternating current.

The particular arrangement illustrated in 50 accompanying Figure 1 is particularly adapted to duplex direct current and simplex alternating current working either independently or simultaneously but it is to be understood that this particular arrangement may be adapted to duplex or multiplex 55 alternating current working without departing from the principal features of the invent-

tion; such adaptation consisting only in the incorporation into the system of a multiplicity of parts pertaining to the alternating current system and the inclusion of 60 selective means in the alternating current circuits.

Referring to Figure 1, the cable for transmitting the signals is represented at 1 and the artificial cable for balancing is represented at 2, one arm 3 of the duplex bridge being connected to the cable 1 and the other arm 4 being connected to the artificial cable 2.

The arms of the bridge terminate in a 70 differential choke comprising variable inductive coils 5 and 6 in the arms 3 and 4 respectively the function of which is to prevent the condensers 7 and 8 in circuit with the arms, as shown, and having the usual 75 resistive shunts 7' and 8' respectively from practically short-circuiting the cable and artificial line for currents of such frequency as are used in the alternating current system.

Close coupling 9 between the coils 5 and 6 provides for a low effective impedance for outgoing currents entering at the apex and a high impedance for inflowing currents from cable to artificial line.

The two arms of the bridge are joined at the apex by a resistance 10 and connection is taken therefrom to the direct current and the alternating current transmitting apparatus, the respective circuits therefor thus 90 being in parallel between the bridge and earth.

Referring to the direct current transmitting apparatus 18', this apparatus may be of any usual or convenient type but the current generated is caused to pass first through a transient moderator before passing through the ordinary apex inductance to the bridge apex.

The apex inductance represented at 11 100 conveniently conforms to usual practice and incidentally assists in preventing alternating current signals from being by-passed through the direct current transmitting apparatus. The transient moderator is a device which, owing to its characteristic of impeding the passage of alternating currents between certain ranges of frequency, prevents or tends to prevent the local alternating current receiving apparatus from being 110 improperly actuated by locally transmitted direct current as a result of imperfection in

bridge balance. The transient moderator illustrated in Figure 1 comprises inductances 12, 13 and 14 and condensers 15, 16 and 17, connected substantially as shown.

5 One lead 18 from the direct current transmitting apparatus 18' makes connection with a closed circuit 19 having the inductance 13 and condenser 16 in parallel. Circuit 19 makes connection with a closed circuit 20 having inductance 12 and condenser 15 in parallel and this latter circuit is directly connected to the apex inductance 11.

10 The other lead 21 from the direct current transmitting apparatus is earthed at 22 and 15 a connection 23 is taken from this lead to the connection between the closed circuits 19 and 20, inductance 14 and condenser 17 being in series with connection 23.

15 A further lead 24 is taken from earth 20 to the double relay 25 of the alternating current transmitting system and a condenser 26 placed in series therewith, such condenser serving to prevent direct current signals being by-passed through the alternating current system. The other lead 27 from the relay 25 makes connection at or near the bridge apex with lead 18.

20 In direct connection with the relay 25 is the alternating current transmitter 28 of 30 any usual or convenient type.

25 The transmitter alternator 30, motor 31, alternator 32, speed controller 33 and vibrating reed generator 34 of the alternating current system may be of any convenient type and are connected as diagrammatically indicated.

30 The usual inductive recorder shunt 35 across the arms 3 and 4 is provided as shown and leads 36 and 37 from said arms respectively to the direct current receiving apparatus 36'.

40 In circuit with the direct current receiving apparatus, which apparatus is of any usual or approved type, it is preferred to 45 employ a relay screen conveniently comprising inductive coils 38 and 39 wound round a laminated core 40 and there being provided a condenser 41, connections being made as shown.

50 The function of said relay screen is to 55 prevent currents of similar frequency to that used for the alternating current system currents which are liable to be generated by vibrations of the coils, armatures or other moving parts associated with the direct current receiving apparatus from flowing back into the duplex bridge and thereby disturbing the alternating current receiving apparatus.

60 For the purpose of allowing of alteration of the balance of the alternating current receiving system without materially disturbing the balance of the direct current system (which is a practically indispensable refinement when operating duplex) auxiliary

balancing means are placed in circuit with the arms of the duplex bridge. The example of auxiliary balancing means illustrated in Figure 1 is constituted by suitable variable impedances 42 and 43 in circuit 70 with the arms 3 and 4 respectively. One lead 44 to the alternating current receiving system is taken from that side of the impedance 42 remote from the bridge apex and the other lead 45 to the alternating current receiving system is taken from that side of the impedance 43 nearer to the bridge apex. Alternately, the leads 44 and 45 may be taken from the opposite sides of the respective impedances 42 and 43 as represented by 80 the dotted line 46.

85 By reason of providing said auxiliary balancing means a refinement of the balance for the alternating current system may be obtained without disturbing that of the direct current system.

90 Leads 44 and 45 connect the amplifier 48, 49 for the alternating current receiving system to the duplex bridge, as shown, and in circuit with the lead 45 is a condenser 47 which is adapted to prevent the amplifiers 48 and 49 in circuit with the leads 44 and 45 from by-passing the incoming direct current signals to a harmful extent.

95 To further assist in removing the effect of the direct current incoming signals a mutual inductive coupling 47' is preferably inserted in the leads 44 and 45 intermediate the bridge arms 3 and 4 and the amplifier 48, each coil of such coupling being in parallel with a condenser 48'. Additionally a non-inductive resistance may be connected in the lead 45 as shown at 45'.

100 Connection is made from the amplifier 49 through a transformer 50 to polyphase relays 105 51, the function of the transformer being to ensure that the circuit leading up to the relays shall be characterized by an inductive impedance so as to stabilize the deflections of the relays, as well as to ensure that the current supplied to the relays contains no unidirectional component and also to provide an efficient coupling between the relays and the output circuit of the amplifier if they are of widely different impedances.

110 The polyphase relays illustrated in Figure 1 are of the known type incorporating two coils disposed in magnetic fields which are excited by out-of-phase currents provided by the alternator 32 and act as relays for the operation of any further desired devices such as a suitable receiver 56.

115 The current supplied to the fields of the relays by the alternator 32 is as nearly as possible of the same frequency as that which constitutes the incoming alternating current signals.

120 The said polyphase alternator further excites a phase shifting transformer 52.

125 The adjustable phase output of this trans-

former is impressed upon the cable system by means for the variable resistances 53 and 54, connected as shown, resistance 54 being in series with the cable 1 and resistance 53 being in circuit with leads taken from the cable 1 one on each side of resistance 54 to the transformer 52. A switch as at 55 is also provided in said circuit.

The function of the above described phase shifting transformer is to provide a current of definite phase and frequency for use while adjusting the polyphase relays in a manner well known to persons versed in this art and the said current is not for use either in the transmission or reception of messages.

It should be noted that the motor 31 drives all the other machines through gearing, as shown, and by reason of the speed of the motor being controlled (suitable mechanism, not forming subject-matter for this specification, being utilized therefor) the speed of the machine driven thereby is likewise controlled.

In general, the sudden introduction of an alternating E. M. F. into a cable system will result in a current at some remote point having an integral value over a finite time interval different from zero and greater than any possible integral over a half cycle. Such an integral value is effective in operating a direct current receiving device and to avoid such action we provide a contact maker represented by 29 in Figure 1 in order to ensure that the outgoing alternating current signals are established and dis-established at definite predetermined points in the cycle so as to prevent them from interfering with the direct current receiving apparatus at the remote end of the cable.

A preferred contact making and breaking device according to the present invention is illustrated in Figure 2, in which the circuit *a b* is to be opened and closed subject to the conditions stated above by the key *k*. *c* is a slip ring geared to the alternator generating current for the transmission of the requisite signals, such slip ring making one revolution per cycle. *d* and *e* are brushes, making contact with the slip ring.

The slip ring and brushes are so constructed and so placed relative to one another that the brushes are electrically connected together at that instant during the cycle when it is desired to start the current and are electrically disconnected at that instant during the cycle when it is desired to terminate the current. *f* and *g* are cams geared to the alternator and making one revolution per cycle. Cam *g* works the electrical contacts *m* and *n*, the adjustment being such that contact *m* closes just after brushes *d* and *e* are disconnected and opens just before the brushes are connected together and contact *n* closes just after the

brushes are connected together and opens just before the brushes are disconnected. Cam *f* works the electrical contacts *o* and *p*, the adjustment being such that contact *o* opens briefly while contact *m* is closed and contact *p* opens briefly while contact *n* is closed. *q* is an electromagnet working contacts *r* and *s* and *t* is an electromagnet working contacts *u* and *v*. Contacts *r*, *s*, *u* and *v* are closed by current in their respective electromagnets and open when this current ceases. *w* is a battery supplying current for the electromagnets. The various parts are electrically interconnected in the manner shown in the diagram.

This arrangement performs its function in the following manner:—While the key *k* remains open contacts *r*, *s*, *u* and *v* remain open; hence, circuit *a b* remains open. When the key *k* is closed, nothing happens until contact *m* also closes; this starts the current in electromagnet *t*, closing contacts *u* and *v*. Brushes *d* and *e* are then connected together by the rotation of the slip ring, closing circuit *a b* at the proper instant. Contact *n* then closes; this starts the current in the electromagnet *q*, closing contacts *r* and *s*. Circuit *a b* is now closed through contacts *r* and *u* and remains closed as long as the key *k* is held down. When the key *k* is released nothing happens until contact *p* opens; this interrupts the current in electromagnet *q*, releasing contacts *r* and *s*. Brushes *d* and *e* are then disconnected by the rotation of the slip ring, opening circuit *a b* at the proper instant. Contact *o* then opens; this interrupts the current in electromagnet *t*, releasing contacts *u* and *v*. The apparatus has now returned to its original condition and is ready to go through the same series of operations whenever the key *k* is again depressed.

The desired action can in some cases be secured by placing the alternating current signalling key in the field circuit of the sending alternator without further precautions. The use of the contact maker in the field circuit, operating at a definite point in the cycle, provides a still more perfect control of this source of interference than does the use of the contact maker in the alternator output circuit only.

Summarily it may be stated that the use of superimposed alternating current systems on a cable operating normally with direct current is restricted to currents within a comparatively small range of frequencies. The rapid pulsations used in the direct current signalling set a lower limit and the rapid increase in attenuation along the cable with higher frequencies sets the upper limit.

If the alternating current system be worked duplex, then the two messages must for the above reason be conveyed by cur-

rents of nearly equal frequency. To be specific, suppose that in the arrangement hereinbefore described the transmitting alternator produces 50-cycle current and the receiving alternator 60-cycle current. That means that outgoing messages are at 50 cycles and incoming at 60 cycles.

If the duplex bridge balance were perfect, then the system would be directly 10 available for duplex alternating current working, for the outgoing 50-cycle current would not interfere with the reception of 60-cycle current by the amplifiers and relays. It is doubtful if such a nearly perfect balance can be obtained and maintained so that it becomes necessary to make the alternating current receiving system so selective as regards frequency that imperfections in balance do not interfere with reception at, say, the 60 cycles even though there exists considerable disturbance from the outgoing current of 50 cycles.

We claim:—

1. In a system of multiplex telegraphy 25 duplex bridges, connection therebetween, direct current transmitting and receiving apparatus, alternating current transmitting and receiving apparatus, connection from the bridge to earth, transmitting apparatus 30 connected to said bridge and a plurality of impedances for suppressing such currents resulting from the transmission of direct current as possess a frequency of the same order as that of the received alternating current.

2. In a system of multiplex telegraphy duplex bridges, connection therebetween, transmitting apparatus connected to said bridge, receiving apparatus connected across said 40 bridge and means located intermediate the bridge and direct current transmitting apparatus for suppressing such currents resulting from the transmission of direct current as possess a frequency of the same order 45 as that of the received alternating currents.

3. In a system of multiplex telegraphy duplex bridges, transmission line and artificial line, direct current receiving and transmitting apparatus, alternating current 50 receiving and transmitting apparatus, connection from the bridge apex to earth, closed circuits in series with one another in said connection, a condenser and inductance in parallel in each of said circuits, a connection 55 adjacent one of said circuits to earth, a condenser and inductance in series in said latter circuit, direct current transmitting apparatus in said apex-earth connection, and alternating current transmitting apparatus in 60 parallel with the direct current transmitting apparatus and associated circuits.

4. In a system of multiplex telegraphy duplex bridges, a transmission line, direct current receiving and transmitting apparatus, alternating current receiving and

transmitting apparatus, connection from one bridge apex to earth; a direct current transmitting apparatus located in said connection, impedances also located in said connection for suppressing such currents resulting from the transmission of direct current as possess a frequency of the same order as that of the received alternating current, alternating current transmitting apparatus for transmitting signals 70 over the said line, and means for so introducing the transmitted alternating currents into circuit and removing them therefrom that remote direct current receivers are substantially unaffected thereby.

5. In a system of multiplex telegraphy duplex bridges, a transmission line, direct current receiving and transmitting apparatus, alternating current receiving and transmitting apparatus, connection from one bridge apex to earth, direct current transmitting apparatus located in said connection, alternating current transmitting apparatus for transmitting signals over the said line, and means for introducing and withdrawing the alternating current signalling current at pre-determined phases of the cycle of alternation.

6. In a system of multiplex telegraphy duplex bridges, a transmission line, direct current receiving and transmitting apparatus, alternating current receiving and transmitting apparatus, connection from one bridge apex to earth, direct current transmitting apparatus located in said connection, alternating current transmitting apparatus in parallel with said connection and earth, a transient moderator located in said connection, and means for introducing and withdrawing the alternating current signalling current, 105 pre-determined phases of the cycle of alternation.

7. In a system of multiplex telegraphy duplex bridges, a transmission line, direct current and alternating current receiving apparatus, and a transient moderator, sources of direct and alternating signaling currents, said transient moderator being interposed between said source of direct signaling current and said transmission line 110 for preventing the alternating current receiving apparatus from being affected by interfering currents.

8. In a system of multiplex telegraphy duplex bridges, a transmission line therebetween, a plurality of impedances for preventing locally produced direct current from improperly actuating local alternating current receiving apparatus and the armature of an electric current generator connected to said line, a transmitter in the field of said generator and operation of said transmitter producing signals in the line.

9. In a system of multiplex telegraphy duplex bridges, a transmission line, a trans-

- sient moderator, having a pair of branches connected in series and an intermediate branch connected in parallel with respect to said transmission line, direct current receiving and transmitting apparatus, alternating current receiving and transmitting apparatus, each of said transmitting apparatus comprising sources of energy differing in characteristic from each other and connections between one of said sources of energy and said transient moderator and the line whereby the effect of said other source upon said first mentioned source is substantially eliminated. 65
- 15 10. In a system of multiplex telegraphy duplex bridges, a transmission line, direct current receiving and transmitting apparatus, alternating current receiving and transmitting apparatus, a transient moderator, 70
20 the alternating current generator and transmitter connected to contacts, cams controlling the opening and closing of said contacts, and means for imparting rotary motion to said cams from the alternator. 75
- 25 11. In a system of multiplex telegraphy a duplex bridge, a transmission line, direct current receiving and transmitting apparatus, alternating current receiving and transmitting apparatus, a transient moderator, 80
30 an alternating current generator and transmitter, the generator armature connected to the transmission line, switches in said connection, electro-magnets for opening and closing said switches, a local source for supplying current to said magnets, switches connected to the alternating current transmitter, said latter switches controlled by said magnets and connected to contacts, said contacts controlled by cams, and means 85
35 for imparting rotation to said cams from the alternator so that the alternating current is introduced and withdrawn from the transmission system only at predetermined phases of the cycle of alternations of said current. 90
- 40 12. In a system of multiplex telegraphy, duplex bridges, a transmission line, direct current receiving and transmitting apparatus, alternating current receiving and transmitting apparatus, a transient moderator, auxiliary balancing means variable impedances located in the bridge arm, said alternating current receiving apparatus being connected adjacent said auxiliary balancing means whereby said means render the received alternating current receiving apparatus immune from the effects of locally transmitted currents. 95
- 45 13. In a system of multiplex telegraphy a duplex bridge, a transmission and an artificial line, transmitting and receiving apparatus, a transient moderator, variable impedances in two of the bridge arms, leads from each of said arms to the alternating 100
50 current receiving apparatus, one of said leads located on that side of the impedance in one arm remote from the bridge apex and the other lead located on that side of the other impedance in the other arm nearer the bridge apex. 105
- 55 14. In a system of multiplex telegraphy a duplex bridge, a transmission and an artificial line, transmitting and receiving apparatus, a transient moderator comprising a pair of series branches each containing an inductance shunted by a capacity and an intermediate branch containing inductance and capacity connected in series and disposed in parallel with respect to the transmission line, leads from the alternating current receiving apparatus to the bridge arms, amplifiers in said leads and an inductive coupling intermediate said amplifiers and arms said transient moderator being interposed between the transmission line and a portion of the transmitting apparatus. 110
- 60 15. In a system of multiplex telegraphy a duplex bridge, a transmission and an artificial line, transmitting and receiving apparatus, a transient moderator comprising impedance in series and in parallel said moderator interposed between the transmission line and a portion of the transmitting apparatus connection from the alternating current receiving apparatus to the bridge, said connection including an inductive coupling and means for amplifying the alternating current signals. 115
- 65 16. In a system of multiplex telegraphy a duplex bridge, a transmission and an artificial line, transmitting and receiving apparatus, a transient moderator comprising impedance in series and in parallel and a differential choke in each bridge arm. 120
- 70 17. In a system of multiplex telegraphy a duplex bridge, a transmission and an artificial line, transmitting and receiving apparatus, a transient moderator comprising a plurality of condensers and inductances connected between the transmission line and the transmitting apparatus, and a differential choke in each bridge arm. 125
- 75 18. In a system of multiplex telegraphy duplex bridges, a transmission line, direct current transmitting and receiving apparatus, alternating current transmitting and receiving apparatus, a transient moderator comprising impedance in series and in parallel, inductances in each bridge arm, said inductances being inductively coupled mutually and variably and located in said arms on that side of the direct current and alternating current receiving apparatus adjacent the bridge apex. 130
- 80 19. In a system of multiplex telegraphy a duplex bridge, a transmission and an artificial line, transmitting and receiving apparatus, a transient moderator, leads from

the bridge arms to the direct current receiving apparatus and a relay screen located in said leads.

20. In a system of multiplex telegraphy a duplex bridge, a transmission and an artificial line, transmitting and receiving apparatus, a transient moderator, leads from the bridge arms to the direct current receiving apparatus, two coils in series in one of said leads, said coils mutually inductively coupled, a connection from a point intermediate said coils to the other lead and a condenser in said connection.

21. In a system of multiplex telegraphy duplex bridges, a transmission line, direct current transmitting and receiving apparatus, alternating current transmitting and receiving apparatus, and a transient moderator, connected between said transmission line and said direct current transmitting apparatus and arranged to prevent the alternating current receiving apparatus from being actuated by locally transmitted direct current energy.

22. In a system of multiplex telegraphy duplex bridges, a transmission line, direct current transmitting and receiving apparatus, alternating current transmitting and receiving apparatus, a transient moderator, said latter receiving apparatus comprising two relays for each alternating current signalling channel, an alternating current supply to each field and the current supplied to one field being substantially in time phase quadrature with the current supplied to the other field.

23. In a system of multiplex telegraphy

a duplex bridge, a transmission and an artificial line, direct current transmitting and receiving apparatus, alternating current transmitting and receiving apparatus, a transient moderator, polyphase relays in the alternating current receiving system, independent fields to each relay, an alternating current supply to each field, the current supplied to one field in time phase quadrature with the current supplied to the other field, a phase shifting transformer in parallel with each of said fields, connection from said transformer to the bridge arms, said connection adjacent the transmission line, a key and variable resistances in said connection and said transformer providing a current of definite phase and frequency for use while adjusting the relays.

24. In a system of multiplex telegraphy duplex bridges, a transmission line direct current receiving and transmitting apparatus, alternating current receiving and transmitting apparatus, a transient moderator, an apex inductance, a differential choke, said choke located in the bridge arms, a relay screen, said screen located in the direct current receiving system, auxiliary balancing means and polyphase relays located in the alternating receiving system, means for introducing and withdrawing the alternating current signals at definite phases of the alternation of said current, a condenser in each bridge arm, a resistance in parallel with each condenser and an inductance shunted across said arms.

FREDERICK EUGENE PERNOT.
LESTER JACOB RICH.

Certificate of Correction.

It is hereby certified that in Letters Patent No. 1,599,344, granted September 7, 1926, upon the application of Frederick Eugene Pernot and Lester Jacob Rich, of London, England, for an improvement in "Multiplex Telegraphy," errors appear in the printed specification requiring correction as follows: Page 4, line 58, claim 3, after the compound word "apex-earth" strike out the comma; same page, line 74, claim 4, for the word "current," first occurrence, read *currents*; line 106, claim 6, before the word "predetermined" insert the word *at*; page 6, line 66, claim 24, after the word "alternating" insert the word *current*; and that the said Letters Patent should be read with these corrections therein that the same may conform to the record of the case in the Patent Office.

Signed and sealed this 5th day of October, A. D. 1926.

[SEAL.]

M. J. MOORE,
Acting Commissioner of Patents.
